UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

CASTING FOR LAMP-SOCKETS.

1,146,885.

Specification of Letters Patent. Patented July 20, 1915.

Application filed May 2, 1914. Serial No. 835,936.

To all whom it may concern:

Be it known that I, CHARLES J. KLEIN, a citizen of the United States, residing at Milwaukee, in the county of Milwaukee and 5 State of Wisconsin, have invented new and useful Improvements in Casings for Lamp-Sockets, of which the following is a full, clear, concise, and exact description, reference being had to the accompanying drawings, forming a part of this specification.

This invention relates to casings for incandescent lamp sockets and pendant switches.

The various objects and advantages of the 15 invention will appear hereinafter in connection with the description of a preferred embodiment of the invention shown in the accompanying drawing, wherein—

Figure 1 is a side view of a lamp socket 20 casing; Fig. 2 is a perspective view of the casing shell; and Fig. 3 is a sectional view on the line 3—3 of Fig. 1.

The casing illustrated comprises a cap 1 and shell 2 arranged to telescope together in 25 a conventional manner. Interlocking means are provided to prevent axial separation and relative rotation of the parts when joined. The means illustrated is of the type described and claimed in my co-pending application, filed December 14, 1913, Serial No. 30 807,455, and comprises a pair of inturned beveled catches 3 on the cap and a pair of arc-shaped openings 4 in the shell.

When the parts of the casing are telescoped together the cooperating catches automatically interengage and the cap rim closely encircles the shell margin so that the catches 3 pass well through the openings 4 and effect a secure lock. Furthermore, the 40 socket base 5 which supports the current-carrying parts is snugly inclosed within the casing. As a result of the snug fit of the socket parts within the shell, and of the shell within the cap, finger compression 45 of the shell adjacent to the shoulder 4 to disengage the lock, is rendered difficult. The shell 2 is provided, however, with a small groove or indentation 6 closely adjacent the opening 4 and in a position to be 50 concealed by the rim of the cap when the parts are joined whereby a slight space is left between the overlapped margins for the reception of a convenient tool 7, such as a screw-driver, knife-blade, or the like, by 55 which the interlocking means may be readily

disengaged. When the tip of the operating tool is inserted under the cap margin, a very slight rotative twist thereof, with the edge of the tool adjacent the interlocking means acting upon the shell and the other edge fulcrumed on the unyielding rim of the cap, compresses the shell and separates the catch and shoulder. A very slight upward and rotative turn of the tool handle, with the groove 6 as a bearing, then moves the parts 60 so that the catch 3 is carried out of alignment with the shell opening 4. The tool may then be withdrawn and the shell readily released from the other pair of interlocking means by manipulation at its outer end. 65

The manner of separating the two parts as described is exceedingly simple and rapid. Furthermore, when the socket is itself enclosed by an ornamental husk, such as indicated in dotted lines in Fig. 1, the shell 70 still remains accessible for convenient separation from the cap. An additional advantage is that the casing interlocks so firmly that manual separation of the parts is rendered difficult, and undesirable tampering so with the parts accordingly obviated to a large extent.

What I claim as new and desire to secure by Letters Patent is:

1. In a casing for lamp sockets, a cap having a relatively unyielding margin, a shell having a relatively resilient margin snugly telescoping within said cap margin, and complementary parts on said margins automatically interlocking when said cap and shell are axially telescoped, one of said margins having an offset portion contiguous to said interlocking part thereon and partially overlapped by but spaced from said other margin, said offset portion and said margin 90 overlapping the same providing spaced bearings for an operating tool insertible therebetween and rotatable for compressing said shell margin and thereby disengaging said interlocking parts. 95

2. In a casting for lamp sockets, in combination, a cap having a relatively rigid margin, a shell having a relatively resilient margin snugly telescoping within said cap margin, one of said margins having a shoulder and the other having a radial catch to automatically interlock with said shoulder when said parts are axially telescoped and to be released by radial compression of said shell margin thereat, and one of said margins 100

105

110

having a radially offset portion spaced from the other and contiguous to the interlocking element thereon and to the edge of said cap margin, said offset portion affording entry 5 between said overlapping margins for an instrument to effect disengagement of said interlocking elements, as described.

In witness whereof, I have hereunto subscribed my name in the presence of two witnesses.

CHARLES J. KLEIN.
